CLAIM

The ornamental design for a friction stir welding tool assembly, as shown and described.

DESCRIPTION

1. Friction stir welding tool assembly

1.1 : Top

1.2 : Bottom

1.3 : Front

1.4 : Back

1.5 : Left

1.6 : Perspective

1.7 : Right

This design relates to a friction stir welding tool assembly. The broken lines in the Reproductions show portions of the friction stir welding tool assembly that form no part of the claimed design.
